UNITED STATES PATENT OFFICE.

BENJAMIN RASTALL, OF VIOLA, WISCONSIN.

FLOOD-GATE.

SPECIFICATION forming part of Letters Patent No. 729,962, dated June 2, 1903.

Application filed February 7, 1903. Serial No. 142,309. (No model.)

To all whom it may concern:

Be it known that I, BENJAMIN RASTALL, a citizen of the United States, residing at Viola, in the county of Richland and State of Wisconsin, have invented certain new and useful Improvements in Flood-Gates, of which the following is a specification, reference being had to the accompanying drawings, forming a part thereof.

10 The main objects of this invention are to automatically release the water from a dam or waterway to prevent bursting or injuring the dam or other structure confining the water and to prevent damage by overflow in 15 case of floods or abnormal supply, also to regulate the flow or discharge from the dam or waterway below the crest or top of the dam, and generally to improve the construction and operation of automatic safety and 20 regulating gates of this class.

It consists in certain novel features of construction and in the arrangement and combinations of parts, as hereinafter particularly described, and pointed out in the claims.

25 In the accompanying drawings like letters designate the same parts in the several figures.

Figure 1 is a front elevation of a double flood-gate embodying my improvements. 30 Fig. 2 is a horizontal section of the same on the line 2 2, Fig. 1. Fig. 3 is an elevation of the inner face or water side of one shutter. Fig. 4 is a vertical section on the line 4 4, Fig. 1; and Fig. 5 is a similar section on the 35 line 5 5, Fig. 1.

Referring to the drawings, *a a* are the uprights; *b*, the sill at the bottom of the gate-frame, which, however, may be of any construction suited to the conditions of the case.

40 In the present instance the frame is shown as made of wood; but it may be made of any other suitable material, such as iron or steel. The uprights *a* are preferably formed on their inner sides, as shown, with vertical offset sets or shoulders *d*. In this frame are hinged at the sides on vertical axes a pair of shutters, each composed of uprights *e* and *f* and cross-bars *g*, spaces or openings being left between the cross-bars. The uprights *e* are 45 provided at the ends with trunnions *h*, which are fitted to turn in sockets in the sill *b* and the beam *c* and which may be formed by the

protruding ends of round metal rods passing through the uprights *e*, as indicated by dotted lines at the left in Fig. 1. The outer upright *e* 55 of each shutter is preferably rounded on the outside to fit into and turn in the adjacent uprights *a* of the frame and is formed with a vertical offset or shoulder to close against the shoulder *d*, form a tight joint, and relieve 60 the trunnions *h* or hinges of the shutters from strain when the shutters are closed. The inner uprights *f* of the shutters are formed on their inner faces with opposing vertical offsets or shoulders, one of which 65 overlaps the other when the shutters are closed to form a tight joint and enable the overlapping shutter, which is provided with bolts, detents, or other fastenings, as herein-after explained, to hold the other shutter 70 closed without additional fastenings.

On their inner faces or on the water side (indicated by the arrow in Fig. 2) the shutters are provided with slides or valves movable vertically in cleats or guideways *i* on the 75 uprights *e* and *f* and having regularly-spaced cross-slats *j*, which are adapted to close or regulate the size of the openings between the cross-bars *g* of the shutters. These slides are provided at or near the top and at the sides 80 with vertical racks *k*, engaged by pinions *l* on cross-shafts *m*, which are supported at their ends by bearings on the uprights of the shutters. Each shaft *m* is provided, preferably at its outer end, with a lever-arm *n*, 85 loosely mounted thereon and carrying a reversible pawl *o*, which is adapted to engage with and turn the adjacent pinion *l* in either direction for raising and lowering the slide or valve. Each lever-arm is held in an upright 90 position when not in use by a bail *p* or other fastening, and each slide or valve is locked and held in place by a weighted dog *q*, pivoted to the outside upright *e* of each shutter in position to engage with the adjacent pinion *l*. Each of these dogs is provided with 95 a chain *r* or other connection to disengage it from the associated pinion when the slide or valve is to be raised or lowered.

The inside upright *f* of one of the shutters 100 which closes over the other is provided at its upper and lower ends with vertically-movable bolts *s*, adapted to engage with keepers *t* on the gate-frame to hold the shut-

ters closed. These bolts are beveled or rounded at the ends, as shown in Fig. 5, so as to automatically slip into engagement with the keepers when the shutters are closed, and 5 the lower keeper is provided with a roller *u*, with which the lower bolt engages to facilitate the withdrawal of said bolt when the shutters are subjected to the pressure of water tending to open them. *v* is a lever fulcrummed to the upright *f*, to which the bolts *s* are applied. It is provided at one end with a vane *w*, and it is connected on opposite sides of its fulcrum by rods *x* with the bolts *s*. When the shutters are closed and bolted, 15 this lever, with its vane *w*, stands in a horizontal position, as shown in Fig. 1, and it is normally held in this position by a counter-weight *y* at the end opposite the vane.

A vertically-adjustable chute *z* is arranged 20 to direct water when it rises above a certain level against the vane *w*, and thereby withdraw the bolts *s* and release the shutters. This chute is supported by and movable up and down on the guide-rods 2, which are secured 25 at their ends to one of the shutters, and it is held in any desired position on said rods by set-bolts 3 or by other suitable means.

To prevent sagging of the shutters and to facilitate opening and closing the same, they 30 are provided, as shown in Fig. 1, at the lower end of the uprights *f* with rollers 4, which run on curved horizontal tracks or ways 5. (Shown in Fig. 2.)

My improved flood-gate operates as follows: 35 The shutters being closed and bolted, as shown in Fig. 1, and the chute *z* being adjusted for any predetermined water-level above which damage might result to the dam or waterway or by overflow in case of a freshet or abnormal increase in the water-supply, water rising above the upper end of the chute *z* will be directed thereby against the vane *w* with such force as to tilt the lever *v*, withdraw the bolts *s* from their keepers, and release the shutters, which will thereupon fly open and permit the water to escape without obstruction. 45 The chute *z* may be adjusted to any desired level, thereby permitting more or less overflow without unlocking the shutters. In case of moderate increase in the water-supply the water-level may be kept down within safe limits without opening the shutters by raising the slides or valves so as to uncover the openings between the cross-bars *g* more or less, 50 thereby permitting the escape of the increased supply of water without increasing the overflow at the top of the dam or gate and without draining the dam or waterway.

Various changes in minor details of construction and arrangement of parts may be made within the principle and intended scope of the invention.

I claim—

1. In a flood-gate for dams and waterways, 65 the combination of a shutter hinged at one side on a vertical axis and provided with a detent for holding it closed, a lever connected

with said detent and provided with a vane, and a chute arranged to direct water overflowing the dam or waterway above a certain level against said vane, substantially as described. 70

2. In a flood-gate for dams and waterways the combination of a shutter hinged at one side on a vertical axis and provided with a 75 detent for holding it closed, a lever connected with said detent and provided with a vane, and a vertically-adjustable chute arranged to direct overflow of water above any predetermined level against said vane, substantially 80 as described.

3. In a flood-gate for dams and waterways, the combination of a pair of shutters each hinged at its outer side on a vertical axis, a 85 detent for holding said shutters closed, a lever connected with said detent and provided with a vane, and a chute arranged to direct water from above a certain level against said vane, substantially as described.

4. In a flood-gate for dams and waterways, 90 the combination of a pair of shutters each hinged at its outer side on a vertical axis, a detent for holding said shutters closed, a lever connected with said detent and provided with a vane, and a vertically-adjustable chute arranged to direct water from above a predetermined level against said vane, substantially 95 as described.

5. In a flood-gate for dams the combination of a framework the uprights of which are 100 formed on their inner sides with vertical shoulders, a pair of shutters each hinged at its outer side in said frame and provided with an offset or shoulder arranged to close against the shoulder on the opposing upright of the 105 frame, and each provided on the inner side with a vertical offset or shoulder adapted to close against a corresponding offset or shoulder on the other shutter, a detent for holding said shutters closed, and means for automatically disengaging said detent and releasing said shutters when the water confined thereby rises above a certain level, substantially 110 as described.

6. In a flood-gate for dams and waterways, 115 the combination of a suitable frame having a vertical offset or shoulder on the inner side of one of its uprights, a shutter hinged at one end in said frame and provided on that side with a vertical offset or shoulder adapted to 120 close against the opposing offset or shoulder on the frame, a detent for holding said shutter closed, and automatic means for disengaging said detent and releasing the shutter when the water confined thereby rises above 125 a certain level, substantially as described.

7. In a flood-gate for dams and waterways, the combination of a shutter hinged at one side on a vertical axis and consisting of uprights connected by cross-bars with openings 130 between them, a slide or valve vertically movable in guideways on said shutter and provided with cross-slats adapted to regulate and close the openings between the cross-bars

of said shutter, and means for raising and lowering said slide or valve and holding it in any desired position, substantially as described.

5. In a flood-gate for dams and waterways the combination of a shutter hinged at one side on a vertical axis and composed of uprights and cross-bars with openings between them, a vertically-movable slide or valve having cross-slats for closing more or less the openings between the cross-bars of the shutter and provided at the upper end with vertical racks, a cross-shaft mounted on said shutter and provided with pinions meshing 10 with said racks, a lever-arm loosely mounted on said shaft and provided with a reversible pawl adapted to engage with and turn one of said pinions in either direction, and a detent for holding said slide or valve in adjusted position, substantially as described.

9. In a flood-gate for dams and waterways, the combination of a pair of shutters each hinged at its outerside on a vertical axis, one of said shutters being constructed and arranged to close at its inner side against the inner side of the other shutter and provided at the top and bottom with bolts for holding 25

it closed, a lever fulcrumed to said shutter and connected with said bolts and provided with a vane which stands, when the shutters 30 are closed and locked, in a horizontal position, and a chute arranged to direct water from any desired level against said vane, substantially as described.

10. In a flood-gate for dams and waterways, the combination of a pair of shutters hinged at the outer sides on parallel vertical axes and constructed and arranged to close at their inner sides one against the other, rollers attached to said shutters at the bottom near their inner sides, curved tracks for said rollers arranged to support said shutters in opening and closing, a detent for holding said shutters closed, and automatic means for disengaging said detent and releasing said 45 shutters when the water rises above a certain level, substantially as described.

In witness whereof I hereto affix my signature in presence of two witnesses.

BENJAMIN RASTALL.
